ANIMATED TOY

Lyman Franklin Higgins, Hawthorne, Calif.

Application November 9, 1956, Serial No. 621,334

4 Claims. (Cl. 46—131)

My invention relates to animated toys and specifically to that type of toy which is worked by air led through a tube from an air pump, collapsible ball, or the like operated by the user, to parts operated by the displaced air and arranged within the toy.

Many toys of the type described have been produced, generally in the form of an animal such as a frog or small rabbit which can be made to progress by a more or less life-like series of leaps but the appeal of such toys is somewhat limited by the restricted automation of the animal or the like.

The toy of my invention not only simulates the action of an animal or bird but produces a life-like semblance of the action of the subject by changes in posture as the action progresses, and effects the movement of the subject by means which act in a manner different to that of the operation known to give the toy a novel and interesting quality.

It is an object of my invention to provide an animated toy in the form of an animal, bird or other figure balanced upon a support in an unusual manner and with unusual modes of action, the figure carrying a load which it lifts from a lower to an upper position in a life-like manner.

Another object of my invention is to provide an animated toy of the kind described which is inexpensive to produce and simple in construction.

A still further object of my invention is to provide a toy of the kind described which may be produced in a variety of forms in some of which various parts of the body may be caused to move although substantially the same method of operation is used in all forms.

Yet another object of the invention is to provide a novel method of causing animation in a toy of the kind described.

Still further objects and features of my invention will appear from a study of the following specification and accompanying drawings illustrating by way of example a preferred embodiment thereof.

In the drawings:

Figure 1 is a perspective view of my invention embodied in a toy bird perched on a length of line and simulates the appearance of the bird before commencing to lift a relatively heavy load, here shown as a length of belt.

Figure 2 illustrates the position of the bird on having completed its lifting movement.

Figure 3 is a front view of the bird in the position shown in Figure 1, the belt being merely indicated in order to show details of the body.

Figure 4 is an elevational view showing a modified hand-held pump which may be used to operate the toy, and

Figure 5 is an elevational view of a modified air bulb which may be used to manipulate the toy.

Referring now to Figure 1, the numeral 10 indicates generally the body of the bird, which is hollow and light in weight. The body may be molded from any suitable

2

plastic. Numeral 11 indicates the head of the bird which is also a hollow piece produced in any suitable way.

The head 11 comprises a bill 12 which is open, providing a slot 13, a throat portion 14 and a back of the neck portion 15 which is extended further from the head than the throat portion. The throat and the back of the neck portions are covered by a plate 16. A small hole 17 is provided through both sides of the front lower edge of the throat portion. The head is wider toward the back as indicated at 17a, Figure 3, than forwardly of that point.

The body portion 10 comprises a back portion 18, shoulders 19 which frame an opening 20, an under body or breast 21 which is provided with openings 22 and 22a, legs 23 and tail 24. The opening 20 is preferably narrower than the rear portion 17a of the head of the bird. Holes are provided at the front top edge of the breast portion of the body aligned with the holes 17 in the front of the throat. A pivot pin 22b is passed through the holes in the shoulders and neck, thus pivotally mounting the head on the top front portion of the body for a limited relative pivotal movement therewith.

The rear end of the body is provided with an opening 25 below the root of the tail and a small hole below 26 the tip 26 of the wings and above the tail. The tail itself is provided with a slot 27 (Figure 3).

The operative mechanism comprises a bladder or small rubber balloon 28 which is inserted in collapsed condition through opening 25 so that the front end lies under plate 16. The balloon in collapsed condition is too wide to fall through the breast openings 22 and 22a.

The rear end of the balloon 28 is secured over one end of a connector 29. An air tube 30 is fitted over the opposite end of the connector 29.

In inserting the balloon 28 the connection is pushed with the balloon through opening 25 but the air tube 30 is squeezed through slot 27 to position the tube in the small opening 26 above the tail which is too small to permit the connection 29 to pass through. The described construction holds the balloon in place in the body of the bird while leaving the balloon freedom to take up the position needed in operating the toy.

The bird's body is supported on legs 23 preferably molded as a unit with a plate 31 connecting them and with a tubular piece 32 around which the bird's claws 33 are indicated. A short length of tube 34 is secured in the tubular piece to secure lateral stability of the bird on a cord or line 35 stretched between two points, as for instance by tying one end to the back of a chair with the other end held in the hand of the user or tied under tension to the back of another chair.

The light weight body of the bird is balanced upon the cord by the weight of the article or load, which is heavier than the body, carried in its beak. A loading element in the form of a fairly stiff solid leather belt 36 serves the purpose very well if the belt curvature brings the free end to the rear of the cord, as shown in Figure 1, to bring the center of gravity of the bird and belt to the front of the cord. The bird will balance in a sharply downwardly inclined position which is very realistic and quite mystifying.

The device may be operated by any suitable hand pump such as those shown in Figures 4 and 5.

In Figure 4 a small hand pump 37 is used of the kind fitted with the usual non-return valve (not shown) and used for pumping up beach balls or other similar inflated articles. The pump is modified by soldering a cap over the end of the pump and fitting it with a connection 38 to receive the end of tube 30. A vent hole 39 is provided in the cap which can be controlled by a finger tip of the user who manipulates the device as later explained.

In Figure 5 a hand bulb 40 of the usual type provided for manipulating air operated devices is shown which is modified by providing the cap 41 of the bulb with a vent hole 42. A check valve 43 is mounted in the end of the bulb as in the usual form of the article.

While the wings of the bird illustrated are merely molded representations, it is possible to form them separately from thin sheet plastic and attach them to the shoulders by flexible tape to form hinges, and to provide openings in the sides of the body under the wings near the shoulders so that as the bladder 28 is inflated the wings will stand out from the body and other comic effects may be obtained which are intended to be included in the scope of the invention as defined by the claims.

Operation

If the bird is placed on the cord without the belt or similar load in its beak, it will hang upside down as is to be expected, with its center of gravity under its point of suspension.

When the bird is rotated upwardly and a stiff belt or similar load placed in its bill as shown in Figure 1 the bird will balance in the approximate position shown in Figure 1 for the reason that the center of gravity of the belt is behind the cord 35 because of the length of belt extending rearwardly of this center when the bird is in a more downward position. The head of the bird therefore is rocked back on pivot 22b until the wide part 17a of the head contacts the shoulders of the body and will then push the body upwards about its point of support on cord 35 until balance is achieved. The weight of the belt holds the head 11 downwardly with the result that the belt is still hanging with most of its length spaced away from cord 32.

When bladder 28 is inflated it bears against plate 16 and would rock the head forwardly of the center of gravity but for the fact that the body of the bird is light and therefore the reaction of the weight of the belt causes the body to rotate on the cord maintaining the equilibrium of the system but bringing the belt nearer and nearer the cord until the belt contacts the cord and the body of the bird is in the nearly upright position shown in Figure 2.

The movement of the bird can be made life-like by manipulating the air pumps and vent holes 39 or 42 so that the bird seems to lift the load in a series of jerks, sagging a little between each jerk, the latter effect being achieved by letting a little air escape through the vent holes which otherwise are kept closed by a finger tip of the user.

A further effect of the bird puffing out its chest with the effort of lifting is achieved by the bulging out of the bladder 28 through the openings 22 and 22a in the bird's chest, preferably the bladder being of a color such as pink which is a normal chest marking of some common birds.

The tube 30 is preferably made of light transparent plastic material which is inconspicuous and also does not interfere with the movements of the bird, though it should preferably be looped around the cord 35 as shown in Figure 2 to take some of the weight of the tube off the bird.

It is believed that the use of a load supported by a part movably mounted on a body lighter than the load and causing the body to balance on a support in one position in which the load is spaced laterally from the support and then causing the movable part to move on the body so as to bring the body to a higher position by the use of a distendable member located in the body and acting to bring the load closer to the support when said member is distended by fluid pumped into it by the user constitutes a novel manner or method of operation and is therefore claimed as a feature of my invention.

While a preferred embodiment of the method of my invention and means of carrying it into effect has been

specifically described and illustrated, it is to be understood that various changes may be made in the described embodiment without departing from the scope of the invention as defined by the appended claims.

5 What I claim is:

1. A fluid operated animated device comprising: a hollow body; parts immovably connected to said body; a support on which said immovable parts are rotatably mounted; means movably mounted on said body and extending from within to outside of said body; a loading element carried by said means movably mounted exteriorly of said body, and effective to balance the body in a downward position until the device is operated; distendable means arranged within the body and adapted

10 when distended to engage with the portion of the movably mounted means extending within the body and move it to change the position of the center of gravity of the device and loading element and raise the device to another position on the support; and means for controllably 15 forcing fluid into said distendable means; and a flexible conduit connecting said latter means to said distendable means.

2. A fluid operated animated device as set forth in claim 1 and in which said means for forcing fluid into 20 said distendable means comprise: fluid pumping means adapted to be operated by the user; said pumping means being provided with an aperture through which fluid under pressure may escape under control of the operator.

3. An animated device, comprising: a hollow body; a part pivotally mounted on said body and extending from within to outside of said body; a filamentary support for said body; parts immovably connected to said body by which said body is mounted for free part rotational movement about said filamentary support; a loading element 30 heavier than said body carried by said pivotally mounted part and extending below and across the point of support of the body so as to balance the device above said support in one position; distendable means arranged within said body and adapted when distended to engage with the portion of said pivotally mounted part within the body and rock said part about its pivot and thereby alter the center of gravity of the device to cause it to assume different positions on its support, the parts immovably connected to the body maintaining at all times their rotational contact with the support; and means for selectively distending said distendable means.

4. An animated device comprising: a hollow body; a part pivotally mounted on said body and extending from within to outside of said body; means immovably connected to said body by which said body is mounted for free part-rotational movement on a support; a loading element heavier than said body carried by said pivotally mounted part and extending below and across the point of support of the body so as to balance the device above said support in one position; distendable means arranged within said body and adapted when distended to engage with the portion of said pivotally mounted part within the body and rock said part about its pivot and thereby alter the center of gravity of the device to cause it to assume different positions on the support, the means immovably connected to the body maintaining at all times their rotational contact with the support; and means for selectively distending said distendable means.
